(57) **CLAIM**

The ornamental design for a textile, as shown and described.

DESCRIPTION

FIG. 1 is an enlarged top plan view of a textile showing our design;

FIG. 2 is an enlarged bottom plan view thereof;

FIG. 3 is a further enlarge section of the top plan view thereof; and,

FIGS. 4—15 are cross-sectional views as indicated in FIG. 3. The textile has been shown broken away in FIGS. 1—3 to indicated indeterminate length and width.
